[57] CLAIM

The ornamental design for an abrasive mitten, as shown.

DESCRIPTION

FIG. 1 is a bottom plan view of an abrasive mitten showing our new design;

FIG. 2 is a right side elevational view thereof;

FIG. 3 is a top plan view thereof;

FIG. 4 is a left side elevational view thereof;

FIG. 5 is an end elevational view taken from the bottom of FIG. 1;

FIG. 6 is an end elevational view taken from the top of FIG. 1; and

FIG. 7 is an enlarged fragmentary perspective view of an individual scraping element.
